FREIGHT LOADING

Sulo Michael Nampa, Detroit, Mich., assignor to
 Evans Products Company, Detroit, Mich., a corporation of Delaware

Continuation of application Serial No. 434,357,
 March 12, 1942. This application April 9, 1947,
 Serial No. 740,330

43 Claims. (Cl. 105—369)

1

This invention relates to improved loading apparatus adjustable and widely adaptable to hold freight articles of different types in vehicles or storage spaces, and more particularly to improved equipment of this nature built into or combined with a vehicle, such as a railway freight car, to hold (that is, to brace, support or carry, space wedge, or to provide shelves, partitions, or bins for) a wide variety of packages or parts during shipment.

An object of my invention is to provide apparatus or equipment of the type described above which is advantageously combined with the structure of a railway freight car (although it will be understood that this or similar equipment may be used in other vehicles or spaces), to be of minimum practical weight and cost and yet be sturdy enough for all service demands.

Another object is to provide such equipment so that the several portions to be adjusted may be released, moved to their new positions, and relocked or fixed with a minimum in effort and without extensive tools or special equipment. More particularly, it is desired here to use a double tilting motion for removing or adjusting certain of the members.

Another object is to provide equipment of this type which is strong and also low in cost and weight because of the use of tooth-like projections to form the engaging portions to hold the several parts in adjustment, and, more particularly, to permit a very close spacing (of the order of $\frac{1}{2}$ inch) between adjusted positions, moving vertically or horizontally—this to be achieved by the above teeth.

Another object is to provide such equipment embodying adjustably supported side wall members, and cross members carried thereby, the arrangement being particularly characterized in that, while supported by the side members, the cross members may be moved therewith to desired positions of adjustment.

Further objects of the invention are to provide improved loading members per se, in addition to providing improved combinations of utilizing such members.

Other objects of this invention will become apparent from the following specification, the accompanying drawings, and the claims herein-after set forth.

For a better understanding of the invention, reference may be had to the accompanying drawings forming a part of the specification, wherein:

Fig. 1 is a perspective view looking into one end

2

of a partly loaded freight car equipped with the present invention;

Fig. 2 is a perspective view showing the use of a preferred wedging tool to exert powerful leverage in manually adjusting the ends of the cross bars longitudinally;

Fig. 3 is a perspective view of the other end of this same tool;

Fig. 4 is a side or partly perspective view looking in through the door opening at one end of a side bay member or horizontal side member in place;

Fig. 5 is a perspective view generally like Fig. 1 but showing special vertical bars and horizontal bars forming part of a central longitudinal partition for bins, or the like, and also a rotatable or tiltable cross bar in the foreground;

Fig. 5A is a section taken on the line 5A—5A of Fig. 5 and showing the intermediate structure of a modified form of cross bar;

Fig. 6 is a side view of one of the horizontal side bay members employing, as compared with Fig. 4, a modified arrangement for providing the tooth-like projections;

Fig. 6A is a view similar to part of Fig. 6 showing a second modified form of bay member;

Fig. 7 is an end view of the bay member shown in Fig. 6;

Fig. 7A is a fragmentary view in vertical section of the bay member of Fig. 4;

Fig. 7B is a view in vertical section of the bay member of Fig. 6A;

Fig. 8 is a plan view of part of the top of the rack on the bay member of Fig. 7;

Fig. 8A is a similar view of a modified form of the top part or teeth of Fig. 7A;

Fig. 8B is a plan view of the bay member shown in Fig. 6A;

Fig. 9 is a top view of the hanger portion of Fig. 7A;

Fig. 10 is a view similar to Fig. 7 showing the bay member tilted to disengage the two sets of teeth;

Fig. 11 is a schematic partial sectional view of one side of one end of the wall of a freight car equipped with this invention;

Figs. 12, 13, 14, 15 and 16 are enlarged views in horizontal section based on Fig. 11;

Fig. 17 is a transverse sectional view showing a removably mounted door post;

Fig. 18 is an elevational view taken along the line 18—18 of Fig. 17;

Fig. 19 is a top plan view of the post, removed from its holding sockets in the car, taken along the line 19—19 of Fig. 17;

Fig. 20 is a section on the line 20—20 of Fig. 17;
Fig. 21 is a plan view of the cross bar assembly with portions broken away;

Fig. 22 is an elevation of the structure of Fig. 21;

Fig. 23 is a section taken on the line 23—23 of Fig. 21;

Fig. 24 is a section taken on the line 24—24 of Fig. 22;

Fig. 25 is a section taken on the line 25—25 of Fig. 21;

Fig. 26 is a plan view of a modified form of cross bar with a portion broken away; and

Fig. 27 is an elevational view of a portion of the structure of Fig. 26.

Referring to the invention and to the drawings in general, and mainly to Figures 1, 2, 11 and 13, it will be seen that my loading or holding apparatus as combined into the structure of a vehicle, here shown as the conventional type of freight car 1, consists fundamentally of spaced elongated members 16 extending along the sides 10 of the car and specifically being uprights which may be regarded as forming parts of the sides 10, since they are rigidly secured to and so stiffen or reinforce the usual side frame members, such as 13, 66, 67 and 68 of Figs. 11 through 15.

These uprights 16 carry an improved form of holding or engaging shapes 20 which are very closely spaced. In this apparatus as built and very successfully operated under many and varied adverse test conditions of service, this spacing is $\frac{1}{2}$ " for the vertical adjustment, and all the other adjustments are of the same pitch or module. Yet with this close adjustment and with a relatively light structure there is a high strength, due to the arrangement of the holding means as projections or rounded teeth 20 elongated parallel to the car length and normal to the main loads thereon, and due to the use of such projections here in lieu of holes or openings. The uprights 16 thus carry hanging side bay members 31 by an improved and simple organization operated by only two types of tilting to remove or insert members 31 and to change their vertical adjusted positions. No extra latches, or the like, need be relied on to hold or to take loads on members 31.

Members 31 have along their top surfaces a similar form of teeth (or here I may use openings as shown in Figs. 6A, 7B and 8B, although I do not now prefer this last form) and are in turn engaged by a few similar downwardly-projecting teeth 20 on the holding or securing end fittings on the ends of the specially designed cross bars 70. As will be seen, bars 70 rest on the toothed tops of members 31 and may be slid along thereon to any desired adjusted position where the corresponding teeth are engaged and then locked or held against vertical dislodgments (which might occur in the absence of vertical loads on the bars, due to vibrations or vertical bumping of the car) by a means such as a swing-out latch as hereinafter disclosed in detail. This arrangement so that bars 70 rest on members 31, and especially the use of easily curved or rounded teeth, is important since it permits a ready sliding of a bar 70 along members 31 to any desired position without having to lift such bar 70 or going through other difficult operations. Even when a bar 70 is pressing against heavy freight, it may be easily wedged, especially by the tool as shown in Figs. 2 and 3.

In the broader aspects of the invention, no extra holding or locking latches for bars 70 are essential; or, stated another way, under at least certain normal loads all of the major parts of this organization (i. e. the side bay members and the cross bars) are held in place even more firmly by the normal loads themselves.

As seen in Fig. 5, special types of cross bars 100 are provided (usually in limited numbers for each car) to permit the construction of central partitions or bins, or the like, since bars 100 carry two rows of teeth and thus can support other bars. Also, the shorter or half length bars 130 are sometimes useful in bridging across only one-half of the car width. Particularly in bars 100 or 130, and to a considerable extent in all of the bars, it is quite important that they may be slightly extensible or telescopic between their firmly fixed ends, to thus correct for various dimensions and especially changes or errors in the car widths. Also, the rotatable or tiltable feature of the bar 120 is of value in conforming the flat faces of the bar to tilted or angular freight surfaces.

Other advantageous features will be found in the wooden buffer panels 27 and the buffer strips 47 and in the removable door posts and the removable panels 271. The even or horizontal positioning of members 70 is facilitated by the level indicia or level numbers in feet and fractions thereof which are conveniently marked on each edge of each wood panel 27, as shown at 28 in Fig. 1. Still other advantages will be set forth in the following more detailed description.

It may be noted again that constructions according to the disclosures herein have proved themselves to be quite advantageous in service conditions and that numerous advantages accrue from the particular features taught here. For example, cars with loading equipment for the same general purposes are in use and others have been proposed, but the present invention gives appreciable savings in weight and steel required, in cost, in labor time in loading or unloading, and in less damage to freight due to closer adjustments and tighter and more universally adaptable holding or packing in crates (such as C in Fig. 1), packages (such as P in Fig. 1), and many others.

Among the light or heavy and various shaped articles readily handled have been such things as curved automobile doors, rear axles, storage batteries, refrigerators, stoves, and things in light cardboard cartons. As will be seen, the members 70 may also serve as shelves for multiple decking and as temporary platforms for the loading crews.

Referring more particularly to the drawings (particularly Figs. 1, 4 and 11 through 15), the numeral 1 designates a freight car which, as shown herein, may be of the conventional, wide, double door or automobile type. When equipped with the apparatus of the present invention, the car's floor 2 and its wood lined end walls 3 are not changed, but the conventional roof 5 may be strengthened and stiffened by the arched or inclined cross channels 6—6 welded together at the center of the car and welded to the upper side members 7 of the side wall structure. These channels 6—6 carry the welded-on, laterally spaced trolley rails 8—8 extending the length of the car for handling heavy freight in the car, as is well known in this art.

This automobile type car's side walls 10 have

the longitudinally offset double side doors 12, as indicated in Fig. 11. With or without the present apparatus installed, the car is symmetrical or identical end-for-end, so that only one side of one-half of the length of the car is shown in Fig. 11. In installing the apparatus of the present invention in an existing freight car of the general type shown, the changes are in the inner portions of the car's side walls 10 and their doors 12.

The conventional wooden inner lining for the side walls, not shown, is removed to expose the upright, inwardly projecting intermediate side posts 13 which form the main upright strengthening members and roof supports of the car side walls and which in this particular car are in the form of outwardly opening steel channel type members (see Figs. 11 and 13) having the flat inner portions or webs 14, the side portions 15, and the flange portions 15a suitably secured to the side walls 10 as by the rivets 15b, as shown. These uprights or posts 13 are equally spaced along each side of the car except at the wide openings for doors 12. It is desirable to use existing uprights such as the posts 13, suitably modified, as the main longitudinally and laterally spaced upright support members of my freight holding apparatus in order to make the useful space within the car as wide as possible and to save additional weight and expense. However, it will be appreciated that although certain features of this invention are peculiarly applicable to and have a particular cooperation with freight car structure, yet most of the features of this invention may be applied not only to many types of freight cars but to other vehicles or enclosures, such as trucks, holds of ships, cargo airplanes, storage rooms, and the like; and the application of apparatus of the general type disclosed herein to other types of side uprights will be apparent from the present teachings. Also, if properly spaced side uprights are not available or readily usable, it is intended that there will be supplied suitable uprights carrying the two rows of rack teeth, or the like, as herein-after described in greater detail.

The vertical steel post plates 16 having vertically spaced holes 17 (Fig. 13) are suitably secured to the side uprights of the vehicle, as by being welded at the holes 17, along their other exposed edges if desired, or to the inner face of the web member 14 of each of the uprights or channels 13 extending from the car floor to its roof. Thus, any rough projections formed by the welds will be countersunk in the holes so that there will be no sharp projections which could tear freight packages.

An important feature of this invention is the provision of a continuous row or series of uniform teeth, projections or corrugations 20 carried in a strong manner by suitable uprights, such as the channels 13 here, and with these teeth facing in a direction normal to the car sides either in or out, but preferably facing outwardly or away from the inside or center of the vehicle or storage space, as shown. As will be seen in the drawings, the teeth are uniformly curved or rounded in cross section and are evenly spaced, as shown, so one set of such teeth will easily fit into another such set and so the thick base portion of each tooth will give a strong securing means. As will be understood by those skilled in this art, teeth of the general type described herein will be materially stronger than perforations in a plate and are not as apt to be

torn out as are various shaped holes or perforations. This is particularly true of the teeth along the side uprights 13 and on the corresponding side hangers of the members 31. Also, the use of such projections or teeth will, as a practical matter, permit a lighter structure to be built within the usual cost limitations.

As shown in Fig. 13, plates 16 are materially wider than web portions 14 so that they extend out an equal distance to each side of the side portions 15. Plates 16 carry on their inner surfaces the rack members. In the form best shown in Figs. 4 and 7 the teeth 20 are cast in a plurality of short lengths of cast steel rack bars which are welded onto the plate 16. The bars 35 are uniformly arranged end-to-end to each other, so as not to interfere with the uniform spacing of the teeth 20 throughout the entire length of the long rack thus formed, and which rack extends from adjacent the floor to adjacent the roof of the car. As will be apparent, these members 16 (which in an illustrative case, may be $\frac{1}{4}$ " thick and 7" wide) not only form a strong support for the teeth 20 but are also integrally united with the uprights 13 to materially strengthen the car walls. It will, of course, be understood that these teeth 20 may be formed by forging or by other known methods.

The foregoing arrangement enables use of the short lengths of cast rack bars and requires little initial expenditure in tooling; however, for quantity production it would be preferable, to integrally form the outwardly-extending holding means or the teeth on the side posts or the side post plates 16, for example, by rolling in suitably formed rolls when the plates are rolled at the steel mill, as will be understood by those versed in this art. Thus, the separate rack pieces are omitted. The integral teeth are formed much more cheaply and in or as a part of a continuous piece of any desired length so that there is no welding between the teeth from floor to ceiling. It will be apparent that this method and arrangement is not only materially cheaper and stronger but saves an appreciable weight of steel.

In general, it is to be understood that any of the various known or desirable standard structural steel shapes or specially formed shapes may be employed for the normal side posts and the two types of door posts, as well as for the side or bay members and other portions of this organization; and it will be apparent that where this equipment is to be manufactured and installed at the time the car is originally built, it will be economical, if sufficient numbers are made, to have the teeth for the various members initially or originally rolled into the structural steel shapes themselves, instead of being rolled into separate plates like 16. Of course, the structural steel shapes may be made extra strong to take care of the extra loads, if desired.

Referring to Figs. 1, 11 and 12, the one-piece plywood lining panels 27, which here are of $\frac{3}{4}$ " plywood, are permanently secured to the car walls between the uprights 13 by any suitable means. As shown in Figs. 1, 11 and 12, these wooden lining members 27 have less width than the space between the edges of plates 16 or 16a, as the case may be, to provide clearance spaces 29 which are quite important and necessary to permit entry of the tooth-carrying projecting portions of hangers 40 (Fig. 4) on the ends of the horizontal longitudinally-extending side support members 31 when members 31 are tilted

about a transverse axis into their entry or removal position, as hereinafter described.

The inner surfaces of the wooden lining members 27 are, as shown, not quite flush with or are spaced slightly ($\frac{1}{16}$ to $\frac{1}{8}$ inch) outwardly from the smooth inner surfaces of plates 16 to serve as cushioning or buffer surfaces over most of the area of the car sides and thus prevent injury to the freight packages. This outward spacing of members 27 prevents interference with the flat outer surfaces of members 31, which would be apt to occur due to manufacturing inaccuracies or warping if the surfaces were to be made flush originally.

Referring to the embodiment of Figs. 1, 4, 7A and 7B, each of the horizontal side members or the bay members designated as a whole by 31 is formed by standard structural steel angles 32 extending from end to end thereof and being of a length nearly equal to the centerline-to-centerline distance of the freight car posts 13 or their equivalents with only sufficient clearance so that they may, if desired, be mounted in an end-to-end horizontal row, as shown at 33 in Fig. 1. The lengths of cast iron racks 35, and which have identical teeth 20, are similarly welded at their edges, as at 34, and end-to-end, to the upper outer surfaces of the short leg of the angle 32, with the exposed weld at the joint 26 recessed in a suitably formed groove between the teeth to prevent rough projections and interferences with the proper meshing of the teeth. As shown, the cast teeth 20 on members 35 have smoothly rounded ends, as seen in plan view.

Referring again to the modification of Figs. 1, 4, 7A and 7B, the structural steel angle 32 has welded to the back or the outer surface of its long leg and near each end thereof two right and left-hand, but otherwise identical, one-piece hanger members (which are preferably drop forged but may be of suitable cast steel) generally indicated by 40, each having a central flat portion 41 welded at its edges, as at 42', to the back of the long leg of angle 32 and having a downwardly-projecting portion 42 with a hole 43 to receive a carriage bolt 45 having nut 46 and with its head countersunk in and securing the rectangular wooden buffer or pad member 47 which projects out even with or preferably slightly beyond the outer surface of angle 32 and its teeth 20 to prevent injury to freight by contact with these metal corners. It will be apparent that wooden buffer members 47 are strongly held but may be readily replaced. In addition, hanger member 40 has a thick integral strength or web portion 49 supporting the tooth-carrying projecting portion 50. The flat side or end portion 51 abuts against the corresponding flat edge surface of the tooth-carrying plate 16 or the corresponding surface of plate 16a to act as lateral stops and to thus prevent lateral movement of side members 31. The teeth 20 on portion 50 are identical with the previously described teeth and are here shown as consisting of four teeth, although five have been found to be a satisfactory number in the designs shown.

These teeth 20 on member 40 are adapted to mesh or engage with any of the outwardly-facing identical teeth 20 on the inside of, or on the flanges formed by, plate 16 on uprights 13 in any desired position of vertical adjustment.

As will appear from Figs. 4, 6, 7 and 10, the teeth 20 on member 40 engaging the similar teeth 20 on uprights 13 are spaced above and outwardly from the outermost surface of the long

leg of angle 32 which engages and rests against or is pressed against the outer surface of plates 16 or 16a. As shown in Fig. 10, the distance L between the lowermost inner corner portion of toothed member 40 or the rounded crown of the end tooth 20 (which may act as pivot here during the tilting) and the uppermost portion or corner of the outer surface of the lower or longer leg of angle 32 is appreciably greater than the thickness T of the plate 16 plus the maximum thickness of toothed or rack member 35, so that when the side member 31 is manually tilted about a longitudinally extending axis, the two sets of teeth 20 come out of engagement with or clear each other.

As will be apparent from Fig. 10, this will permit a very easy manual vertical adjustment of the side members 31 up or down to any desired vertical position on the uprights 13, it only being necessary to grasp the side member 31 and tilt its inner portion inwardly to the desired vertical position, move 31 to the desired position, and then tilt it back again to engage the teeth 20 on members 40 at each end with the corresponding teeth 20 on uprights 13. Also it will be apparent that the side members 31 may be tilted in substantially the same way as just described and as shown in Fig. 10 but with the uppermost outer corner of the angle 32 pushed in to engage the face of plate 16 so that this corner serves as the pivot point during the tilting. Thus, by only a tilting motion or by a pure tilting or rotation, the interfitting and interengaging holding members or teeth 20 are disengaged and the member 31 is then in position for free up or down sliding or adjustment along the side posts. No second or other motion would be necessary here in releasing or moving the member 31 to position for adjustment.

Referring again to Fig. 4, considered with Figs. 7 and 10, it will be seen that the weight of member 31 hangs down from the interengaging teeth 20 and is held against further turning or swinging by the abutting of the outer surface of the upright 16 against the back of the angle member 32. This stable member 31 is also held in place by any weight or load applied down on member 31 so that, in general, no additional securing or holding means is required. However, for occasions where there is little load on certain members 31, or to keep them from jumping or vibrating in the moving freight car, I provide a suitable extra latch to prevent 31 from swinging out, such as the simple spring latch comprising spring 53 bent as shown, in which one end projects through a hole in 31 to serve as the latch while the other end is pivotally held between ears 54. This sort of latch may be partly automatic; that is, it will snap in when 31 is swung into engaged position, but the latch must be pulled out to disengage 31.

It will be noticed that Fig. 4 is a view looking in through the open door 12, so that plate 16 is welded onto the movable end door post, as shown in Figs. 11 and 15. However, everything else here looks as it would if the view were from behind the posts 13.

Referring again to the side or bay members, such as 31, I have described above, in connection with Figs. 4, 7A, 8A and 10, forms using the welded-on cast rack strips or with integrally rolled in tooth-like projections. The general form of these members 31 is, of course, otherwise the same as the further and preferred form of bay member 31', as shown in more detail in Figs. 6, 7, 8 and 9.

In this preferred form the most important dif-

fering feature is the formation of the rack or teeth **20'** extending along the top surface of the angle **32'** by a single, continuous, long strip of corrugated steel **35**, or the like, as shown in Figs. 6, 7, and 8. The teeth **20'** are of the same cross-sectional shape as teeth **20**, but (as shown in Fig. 8) they do not have the rounded edge since this would be difficult to form with the corrugating rolls and is not essential here. In all of these embodiments, these teeth **20** and **20'** have been made $1\frac{1}{8}$ " long. As indicated at **34'** (Fig. 8) the strip **35'** has, at suitably spaced intervals of a few inches, flat or recessed portions formed in an upwardly-projecting tooth to give a flat area for the weld **34'** and thus firmly secure the strip **35'** to the angle **32'**. As will be apparent, this weld **34'** will be within the contour of the tooth and will not interfere with proper meshing of the teeth. This strip **35'** may, of course, be had in strips as long as desired and can be readily cut off to proper lengths. This arrangement produces a strong and yet very cheap set of teeth for an organization of this sort, and it will be apparent that it may, if desired, be used to replace the teeth of the other toothed portions of this whole organization.

As will be seen in several figures, this second form of bay member has the same type of teeth **20** carried on the projecting portion **50'** of the hanger member **40'**, which is generally similar to hanger **40** although it differs somewhat in shape, as indicated below. Here the angle **32'** has a longer depending leg which extends down into a cut out recess in the buffer strip **47'**, to which it is bolted by similar carriage bolts **45'** with recessed heads as shown. Accordingly, the depending portion **41'** of the hanger is slightly longer, although the portions **49'** and **51'** are otherwise of generally similar shape. This hanger member **40'** is secured to the angle by welds in the same fashion as shown in Fig. 4, and one or both of the hanger members **40'** may have a spring pressed latch with operation generally similar to that described with respect to Fig. 4. However, its structure is slightly different in that the spring **53'** is bent and shaped as shown and holds and biases the plunger **55'** which has a reduced intermediate portion **57'** to which the intermediate portion of the spring **53'** is secured. The upper end portion **58'** of this spring is suitably anchored to the hanger; for example, by being held in a hole through web **49'**. The shape of the hanger member **40'** is made clearer by a consideration of Fig. 9.

A further form or modification of this bay member is indicated as a whole by **31b** in Figs. 6A, 7B, and 8B which show only the features which are different from the disclosure of Figs. 6-9. Here the row of closely spaced holding means along the top of the angle **32b** is formed by pierced openings **59b** or slots which may extend partly or all the way through the top of the angle as shown. Preferably, these slots are punched all the way through by a multiple punch on $1\frac{1}{2}$ " centers to give the same pitch as mentioned above. It is important that these openings **59b** have rounded ends and filleted or rounded edges, as shown. It will be understood that the downwardly-projecting teeth **20** on the ends of the cross bars **60**, or the like, will mesh with these openings. If necessary, the projecting portion which extends over the outside edge of the teeth along the members **31** may be modified to reach over the outside edge of the angle **32b**.

Figs. 11-16 show the arrangement of the several

types of modified side posts in the freight car structure. Somewhat schematic Fig. 11 shows a plan view of one end of one side of the freight car in which the usual metal outer side wall **10** is braced by the intermediate series of side posts **13**.

Fig. 12 shows a member **66** forming part of the end wall of the car and having the car's wooden end lining **3** secured thereto. Plate **16a** is cut or may be specially formed to provide a plate of lesser width which is secured by welds **18** in holes **17** to member **66** to provide only one row of teeth **20** which are engaged by the corresponding teeth on the ends of dotted-in member **31**. The inside car walls have been stripped, as previously noted, and suitable clips or angles **61** are secured thereto as by rivets **62** and carry, as by bolts **63**, wooden furring strips **64** of suitable thickness, which in turn carry the $\frac{3}{4}$ " thick plywood buffer panels **27** secured by suitable means, such as the nails **65**. Note the provision of the clear space or slot **29** to permit entry and the tilting for removal of the tooth-carrying portion **50** of the bay member **31**. The width of each slot **29** is sufficient to permit the associated bay member **31** to be tilted for removal. It should be noted, however, that if this width were made too small for removal of portion **50** and the members such as **27** (which might be edged with metal along this slot) were put in position after members **31** were in position (or members **31** might be entered through a blocked recess), then it would be impossible to remove members **31** without breaking some parts, and this would make them pilfer-proof.

As shown in detail in Fig. 13, the side posts **13** are here in the form of channels, although it will be understood, particularly by the disclosure of Figs. 14-16, that other forms of structural steel members may be attached thereto, and hence the present invention may be applied to various types of freight car posts. In Fig. 13, the channel **15**, which has been described above, carries and is stiffened by the plate **16** which has the teeth **20** thereon as disclosed above, plate **16** being secured by welds **18** partly or wholly filling the holes **17** provided for this purpose. The welds **19** may also be used if desired.

Fig. 14 shows a structural steel angle **66** riveted at **81** to wall **10** and forming one of the two similar posts on either side of the wide double doors **12**, only one of which is shown in Fig. 11. Angle **66** is stiffened by steel angles **82-82** welded as shown at **83** to carry plate **16**.

Fig. 15 shows an I-beam **67** which is not a part of the original car structure and which carries the plate **16**, as disclosed above. This I-beam **67** forms a removable tooth- or rack-carrying doorway post which may be mounted about in the middle of the openings for one of the doors **12** when the full width of the doors is not necessary and additional loading space is desired. This removable post **67** is disclosed in more detail in Figs. 17-20.

Fig. 16 shows the angle **68** which forms an end of the movable door **12** and has the bent-in portion **87**. This angle **68** is modified by the additional angles **85** welded on as at **86** to carry plate **16** in the manner disclosed above.

Thus bay members **31** may be mounted between the modified posts **66** and **67** and between posts **67** and **68** and, in addition, by omitting post **67**, extra long bay members may be mounted between post member **68** and the extreme right-hand post member **66**, to close the doorway other-

75

wise left open and thus permit full utilization of all space in the car.

Latches, such as the previously described latches 53 and 53' (Figs. 4 and 6), have a particular utility in connection with the just-mentioned extra long bay members. In the present disclosure, the spacing between adjacent side posts 16 is short enough so that one man can readily handle the associated bay members 31. The extra long or doorway bay members may, however, be of such length as to make it desirable for workmen to cooperate in installing them. The just-mentioned latches, which require a manual releasing operation, prevent a workman at one end of the bay member from tilting the bar (thereby releasing it from supporting engagement by the upright posts) until the workman at the other end of the bar is ready and has also released his latch.

In Figs. 17-20 the roof of the car 5 has the side plate or structural member 7 which is secured to structural member 1' forming therewith a downwardly opening channel-like space whose members are part of the original structure. A suitable length of downwardly opening channel 91 is secured in this space, as by welding, and this channel 91 has two $\frac{1}{4}$ " steel web plates 92 secured thereacross, as by welds 92, to form a rectangular box-like recess to receive the reduced upper end portion 93 of the I-beam post 67. Note that the width of the inside to the outside of this box-like recess is greater than the corresponding width of the top 101 of the post portion 93.

In addition, the lower depending portion of member 7 has a spacer member 104 of suitable thickness welded thereto, as at 105'. The post's enlarged lower end portion 94 carries two heavy steel pins 105 welded thereto, as at 106, and these pins project downwardly a depth D, as shown in Fig. 17, and are received in suitable holes 107 through the threshold plate 108 and the car frame member 110. Numeral 2 shows the wood car floor.

It will be noted that the normally unused height H in this box-like recess 114 is appreciably greater than the depth D. Thus, to put this post 67 into position, it is tilted inside the car and its upper end 101 slid into this box-like space 114 so that the top 101 nearly reaches the top of this space. Thereafter the lower end is moved outwardly until pins 105 drop into holes 107 and the outer surface of post portion 93 abuts against spacer strip 104. Thus all normal downward or outward loads will tend to hold this post in position since it can only move upwardly. To prevent upward movement due to bumps, vibration, or the like, there is provided a heavy steel hinged retainer pin 95 having the main post portion 96 secured against loss by the chain 97 welded to pin 95 and to the post as at 97'. This retainer has the hinged retainer portion 98 pivoted by pin 99. As will be seen, when in position, retainer pin 95 will prevent upward movement by abutting against the lower portions of welded-in plate 92.

Referring again to Fig. 11, the panels 27, which are mounted in two open bays inside the door 12 or in its doorway, are not permanently fastened in place but are removably fastened like post 67. These panels 27 may rest against similar furring strip 64 but are not secured thereto. Thus it will be seen that the door 12, which when unencumbered can be slid past the post 66 to open it, has the deeper or thicker but otherwise similar furring strips 64 removably secured thereon as

by means such as the bolts 63 and brackets 61 used for strips 64 in Figure 12. The removable buffer panels 27, are thus supported by but not necessarily otherwise secured to the wood strips 64. These panels are removably fastened in the same or similar manner as disclosed in Fig. 18 for post 67; that is, the panels 27 are provided at their bottoms with pins 105 (Fig. 11) which are received in suitable recesses in the threshold plate of the doorway, and the upper ends of these panels 27 are received in the downwardly opening channel-like space between members 7 and 7' (Fig. 17) and are put in and taken out by sliding up into a clearance space-like member 67. Hinged retainer pins like 95 of Fig. 17 may be provided to prevent vertical dislodgment except that here the pins would come through the panels from front to back. It is thought that, since the organization here is the same, additional illustration is not required, as this structure will be quite apparent from this description to those skilled in the art. Here then we have an easily removable doorway closing arrangement providing the removable or movable posts with their holding means for the side bay members 31 and with the removable buffer panels 27 which are removably secured to the car itself at their tops and bottoms but are supported throughout their heights by engagements with the furring strips 64 which are removably carried by the movable door 12 which can always be readily cleared for normal use as a door by removing the panels and the strips 64. It will also be seen that the door 12 (carrying strips 64) is held or locked in exactly fully open position by the bay members 31 when they are mounted between posts 66 and 67 and posts 67 and 68. Note that members 31 between the post 68 carried on and by the movable door 12 and the removably fixed post 67 will lock the door 12 in open position. The aforesaid doorway arrangement is claimed in applicant's copending application, Serial No. 576,051, filed February 3, 1945, as a division of applicant's parent application, Serial No. 434,357.

Referring back again to Figs. 4 and 6-10, it should be noted that when the bay members 31, 31' and 31b, or the like are in end-to-end alignment along the car to form a continuous side rack, the end teeth 20, or the like, do not abut; that is, there is a one-tooth skip since there is a space S, as indicated in Fig. 6, between the center line of plate 16 and the end of member 31', or the like. Thus the accurate positioning of the teeth of adjacent members 31' is controlled by surfaces 51', which can be made quite accurate, and it is not necessary to try to have abutting teeth in adjacent members 31', which would, of course, be difficult manufacturing operations.

Figs. 21-25, inclusive, disclose one of the more recent preferred forms of cross bar, designated as a whole by 70a. The intermediate portion of the main length of the bar consists of two similar oak strips 111 which are here shown about half size. These wooden strips are stiffened and separated by a steel Z-member which may be rolled or bent into shape. Member 112 has the intermediate portion 113 between the wooden strips and the oppositely disposed side flanges 114 which do not extend quite to the horizontal (as viewed in Fig. 25) surfaces of the strips 111 so that there are two complete faces of the bar 70a in which there is no exposed metal to injure freight. In the other two places, the metal is either flush with or slightly behind the wooden

surfaces. Members 111 and 112 are secured together by carriage bolts 115 having heads 116 and nuts 117 recessed or countersunk in suitable recesses in the wooden members. Jaws or holding units are secured at the respective ends of the bar. The holding unit 121 comprises a generally U-shaped bent steel member 118 shaped as shown. The base portion of the U-member has a stub shaft 119 secured thereto, as by welding. In the middle portion of member 118, welds 122 secure toothed member 125 which is preferably a forging but may be a steel casting.

This member has a stiffening web 123 across its top with an enlarged central portion for the hole 121. The front top portion of this member is recessed as at 124. The lower portion of this recess carries an arrow 171 and the word "lock" to indicate the locking position for the arrow 133 on the top of the member 133. The back top portion of member 121 has two recesses 123 separated by the stiffening web 124. The bottoms of these recesses carry the indicia "open," as shown by numeral 172. The lower face of forged member 125 is substantially flat, except for the front portion which has a suitable number (shown here as seven) of teeth 20 formed therein. These teeth are, of course, identical in form to mesh with the other teeth of this organization. It is important that the extreme lower outer edge of member 125 forms a downwardly projecting hook 129 to engage over the corresponding teeth 20 on member 31. Thus the outer ends of the several teeth 20 are joined together by a rib-like member 129 which, consequently, closes the outer ends of the grooves between the several teeth 20. The rib 129 is thus effective to interlock with the ends of the several teeth which mesh with the teeth 20 and prevent axial movement of the head 121 to the right relative to the member 31, as viewed in Figs. 21 and 22. The other ends of the grooves between successive teeth 20 are closed by the adjacent body portion of the member 125, which body portion, consequently serves to prevent or limit movement of the head 121 to the left relative to the member 31.

It will be appreciated that, in view of the rounded character of the teeth, the cross members 70 may, after having been seated upon the cooperating oppositely disposed members 31, be pushed lengthwise of the members 31, during which movement the cross bar 70 moves vertically sufficiently to enable the crests of the teeth 20 thereon to ride over the crests of the teeth 20 on members 31.

As disclosed above, and in order to prevent vertical dislodgment, there is provided a rotary latch 134 which has an integral pin 132 whose upper portion is formed into a hex 133 to be engaged by a suitable wrench. This latch member may also be a forging. The lower portion of the latch 134 is shaped as shown in the left-hand end of Fig. 21, with a particular portion and with the sides cut away to provide two recesses 136 and 137 to engage the pin 138 and the ball 141. Pin 138 is suitably fixed in recess 139, while ball 141 is slideable in the larger hole 142 and is biased downwardly by a suitable spring 143. After the latch member 134 is positioned, it is permanently locked in place by flat bar 146 which is welded to member 118 as at 147. The parts are shown in Figs. 21, 22 and 23 in the locked position, in which the rounded locking portion is disposed below and in substantially abutting relation to the under side of the flange on the cooperating

wall member 31. In this position, the pin 138 engages the surface 136 and prevents further rotation of the latch member 134 in a clockwise direction, as viewed in Fig. 21. In this position, also, the detent 141 engages the surface 137 and yieldably resists rotation of the latch member 134 in a counterclockwise or unlocking direction. It will be understood, however, that by rotating the nut 133 in a counterclockwise direction, the latch 134 is correspondingly rotated, during which rotation the detent 141 rides along the upper surface 130° of such rotation brings the latch 134 to the unlocked position in which the pin 138 cooperates with the surface 137 to prevent further such rotation, and in which the detent cooperates with the surface 136 to yieldably hold the latch 134 in the unlocked position. This unlocking movement brings the member 134 out from under the flange on the wall member 31 and enables the corresponding end of the bar 70 to be freely lifted away from the wall member.

At the right-hand end of the bar 70, as shown in these figures, the unit is welded directly to the Z-member 112, the member 118 being welded to portions 114 as shown at 119.

As described and claimed (in connection with bar structures per se and combinations embodying such bar structures) in applicant's copending application, Serial No. 121,424, filed October 14, 1949, as a continuation of the copending but now abandoned application, Serial No. 469,719, filed December 21, 1942, as a continuation-in-part of said parent application, Serial No. 434,357, at one of the ends of this bar, but intermediate its gripping or holding means, there is provided a telescopic or extensible means designated as a whole by 175. This unit includes a sleeve 149 which is welded, as at 149', on the stub shaft 119 to secure it to unit 121. This sleeve carries in suitable holes pin 153 having projecting ends which have a limited axial motion in the opposed guide slots 152, which are here shown in half scale, to permit ample travel to take care of any variation of freight car width, or the like. These guide slots are formed in an outer sleeve-like member 156 which is, in turn, formed by the two generally U-shaped members 155 which are welded together as at 157. Members 155 have in their open ends wooden buffer strips 161 which project beyond their ends, as shown, and are secured by through rods 159.

The somewhat earlier form of cross bar, designated as a whole by 70 and shown in Figs. 26 and 27, is in many instances identical with that just described. The intermediate portion and its cross section through the wooden portion correspond to Fig. 25, while the gripping or holding units 121 are also identical. Here at one end, shown as the left-hand end, the holding unit 121 is welded, as at 162, to the Z-portion 112. The other end of the Z-portion carries, as by welds 163, the rectangular box member 167 which forms the inner slide of the telescopic unit, also claimed in said co-pending application, Serial No. 121,424. This member 167 carries on opposite sides the lost motion member which is here designated by the steel washer 168 welded in its similar opening to the sides 167. This washer operates in the relatively short slot 172 which is formed in the sides 70 of the generally similar bent-up steel box member 171 whose outer end is welded at 164 to the other holding unit 121.

As shown in Figs. 5 and 5A, the special type of cross bar 100 is otherwise like bar 70 (or it may be like bar 78) except that this bar 100 has teeth 20

along all or substantially all of the exposed faces or flanges 112a of the modified Z-bar. These teeth may be so positioned by means of cast tooth-carrying racks 35 welded on as disclosed in connection with Fig. 4, or they may be rolled into the Z-bar 112a while it is flat and before it is bent into Z-shape in the manner similar to that disclosed in connection with plate 16. The wooden buffer strips 111a are otherwise like strip 111 except that they are narrower to provide slots or openings 181a behind each set of teeth 20, to receive the latch 134. As will be seen, there is a space provided for the hook portion 129 to engage over the teeth 20. The uses for this type of bar 100 in forming bins, central partitions, and the like, are disclosed above and will be apparent from the suggestions given in connection with Fig. 5.

There may also be provided another special bar 130 which will be identical with bar 100 and, like it, will have the telescopic portion, except that bar 130 is of a reduced or half length so that it may extend partly or half way across the car width, as shown in Fig. 5.

Another special type of bar 120, shown generally in Fig. 5, may be constructed like bars 70, 70a, 130, or 100 except that, as described and claimed (in connection with bar structures per se and combinations embodying such bar structures) in said copending application, Serial No. 121,424, it also includes a rotary or tilting feature which is achieved by building into the bar an axially extending pin received in the sleeve to provide an axial pivot. These two members are secured between the two end portions 121 and the intermediate portions of the bar, and this sleeve and pin include suitable stop means to prevent the bar from coming apart axially.

The wedging or leverage tool shown in use in Fig. 2 and in more detail in Fig. 3, and combinations employing the same are described and claimed in Patent No. 2,466,728, granted April 12, 1949, on applicant's copending application, Serial No. 475,082, filed February 8, 1943, as a division of said parent application, Serial No. 434,357. The tool is designated as a whole by the numeral 200 and comprises a suitable handle 201 suitably secured into a short sleeve 202 which is secured as by welds 203 to the side or main frame plates 204. These relatively heavy stiff plates are rigidly spaced apart by these welds and by pin 205 which is secured into holes 206 in each plate and also serves as a pivot of the freely rotatable sliding roller sleeve 207. The forged steel jaw member 208 is generally U-shaped with opposing faces and with two opposed sets of identical curved teeth 209 which are just like and mesh with teeth 20. As will be seen, this one tool with its two opposed sets of teeth can be used on the right or left-hand sides of the car. The space between the crowns of one of the sets of teeth 209 and the roots of the opposite set corresponds to the thickness of upper or shorter leg of the angle 32 plus the full thickness of rack 35, or the equivalent member. The member 208 is freely pivotally mounted in, and also secured between plates 208 by pins 210 in holes 211. Note that holes 211 go through the corresponding sides or jaws of member 208.

The manner of using the wedging tool 200 is shown in Fig. 2. In this view, a cross bar 70 is supported at its left-hand end upon a previously described wall member 31, and it will be understood that the opposite end thereof may be similarly supported. One face of the cross bar 70 lies against the face of a freight article, and it

will be understood that before resorting to the wedging tool 200, the bar 70 may have been manually moved to a position in which it freely abuts the freight article. With the parts thus preliminarily positioned, the wedging tool 200 may be applied to the wall member 31, by fitting the jaw 208 thereof over the toothed portions of the wall member 31. This brings one series of teeth 209 into meshing engagement with the teeth 20 and brings the other series of teeth into abutting relation, or immediately adjacent, the under side of the flange on which the teeth 20 are supported. Preparatory to this operation, the jaw 208 is rotated relative to the handle 201 so that, when the jaw is applied, as aforesaid, the handle 201 is spaced at a relatively wide angle from the cross bar 70 and the roller 207 is in abutting engagement with the bar 70. Thereafter the handle 201 may be forced into a counter-clockwise direction, as viewed in Fig. 2, which action causes the roller 207 to roll along the face of the bar 70 from its initial point of engagement to a point nearer the end thereof. During and by virtue of this movement, the bar 70 is forced toward the freight article, causing a take-up of any space between it and adjacent articles or between it and the end of the car or an associated bulkhead. If one such advancing movement of the handle is not sufficient to take up all of the space, it will be appreciated that the tool may be removed and re-applied to the wall member 31 at a point further therealong. In most cases the user will find it convenient to retain the tool in its wedging position until after the locking member 134, associated with the bar 70, has been turned into the locking position.

Assuming very close tolerances, it will be appreciated that the holding relation thus afforded would positively require that the bar 70 project at right angles from the associated wall member 31, in which event the respective heads of the bar would be required to be engaged with corresponding projections 20 at opposite sides of the car. Manufacturing tolerances result in some looseness between the parts, which permits a limited departure from the just-mentioned 90° relationship. This fact is advantageous for certain loading purposes. For example, as shown in Fig. 1, the freight articles may not extend entirely across the car. To enable the bar 70 to serve as bulkhead, which positively prevents the freight articles from moving lengthwise of the car and also prevents them from moving crosswise of the car, it is usual, in the practice of the invention, to lock one bar head at a point somewhat nearer the end of the car than the point at which the other bar head is locked. This angled or wedging position of the bar effects the freight holding action just-mentioned, and is permitted by the above-mentioned manufacturing tolerances.

Summarizing the aforesaid general organization, it will be appreciated from the foregoing that in the preferred practice of the invention the car or other storage space is provided with the permanently installed side posts 16 and buffer panels 21, and with the corresponding removable elements for the doorway. Preferably, also, the car is provided with a desired number of bay members, such as 31, and cross members such as 70, and, to handle certain loads, with a desired number of the special bars described with more particular reference to Figure 5. If desired, all bay members may be left in place between associated uprights 16, even when not in use, and the cross bars may be carried by bay

members located near the roof of the car, leaving the entire storage space free for occupancy by loads not suited to the present apparatus. Thus, when not in use, the present loading members do not obstruct or take up otherwise useable space within the car. Preparatory to a loading operation, utilizing the present organization, the bay members 31 may be disposed in appropriate relation, both vertically and lengthwise of the car. Insertion or removal of a bay member 31 is, of course, accomplished by tilting the bar, so that one end thereof is sufficiently higher than the other end as to permit the tooth-carrying portions of the brackets 40 to be introduced through the slots 29, after which the bay member may be restored to a horizontal position, bringing the toothed portions of the bracket 40 behind and into operative relation to the teeth on the associated posts 16. A release of the bar when so horizontally positioned, automatically establishes the vertical holding relationship between the associated toothed surfaces, by virtue of the offset relation of the body of the bay member, all as previously described. Changes in vertical position of the bay members may readily be accomplished by simply tilting the same about their longitudinal axes, which releases the holding engagement, after which the bay members may be manually moved to the desired height. With the bay members in place, cross bars may readily be applied. Prior to application of a cross bar, its locking members 134 are, of course, withdrawn, after which it may be rested on oppositely located bay members. While so supported, the cross member may be manually positioned along the bay members finally to a desired position. When finally positioned, the locking members 134 may be swung into active position. In forming decks, the wedging tool of Figures 2 and 3 is not needed, whereas in forming bulkheads such tool may well be used, as aforesaid, to properly wedge the freight. Bins, partitions and the like may be similarly established, as described with reference to Fig. 5.

As noted above, this invention may be employed in other places than freight cars, and accordingly the terms "freight car" or the like are intended to include other applications where this invention may be usefully employed, as disclosed herein.

Although only several forms of the invention have been illustrated and described in detail, it will be appreciated by those skilled in the art that various further modifications may be made without departing from the scope of the appended claims.

What is claimed is:

1. As a subcombination in adjustable freight loading or bracing apparatus for freight cars, or the like, longitudinally spaced upright posts secured at the sides of the car, each post having a substantially flat face presented inwardly of the car, and having at its opposite face at least one row of outwardly facing tooth-like projections.

2. As a subcombination in adjustable freight loading or bracing apparatus for freight cars, or the like, two series of upright posts arranged along the respectively opposite sides of the car and forming parts of the side frames of the car, the posts of each series being spaced apart lengthwise of the car, and each post having two vertical rows of tooth-like projections extending substantially throughout the height of the car, said rows being spaced apart lengthwise of the car with said projections facing oppositely away from

the freight space between the posts at opposite sides of the car, whereby said projections do not interfere with freight in said space, said projections serving to adjustably support cooperating freight loading means.

3. As a subcombination in freight-holding apparatus for use in a freight car, or the like, an elongated plate-like metallic member adapted to be connected to and become a vertically extending part of the side wall structure of the car, said member having a portion with a row of teeth extending substantially throughout its height, the crests of said teeth extending transversely to the length of the row, said crests and the spaces therebetween being rounded, said teeth being disposed to adjustably secure cooperating freight loading means at desired elevations on said member, said rounded crests and spaces enabling said cooperating means to be slid along said row, with a wave-like motion, while engaging said teeth.

4. As an article of manufacture for use in freight-holding apparatus for use in a freight car, or the like, an elongated relatively heavy metallic member having a row of teeth extending lengthwise thereof, to engage with spaced holding means on cooperating loading means so as to support said cooperating means in predetermined adjusted relation to said member, the crests of said teeth extending transversely to the length of the row, said crests and the spaces therebetween being rounded, said rounded crests and spaces enabling said cooperating means to be slid along said row, with a wave-like motion, while the holding means thereof are in engagement with said teeth, said member including means to secure the same in operative position in said car.

5. As an article of manufacture for use in freight-holding apparatus for use in a freight car or the like, an elongated plate-like metallic member adapted to be connected to and become part of the side wall structure of the car, one face of said plate-like member being substantially planar so that when the post is connected with said face presented to the interior of the car, it affords a non-obstructive freight engaging surface, the other face of said plate-like member being provided with two separate rows of holding surfaces, the respective rows being located adjacent the corresponding side edges of said face and extending substantially throughout the length of the member, the individual surfaces in each row being disposed to adjustably secure cooperating freight loading means at desired elevations on said member, and the space between said rows affording means whereby the post may be connected to said side wall structure.

6. As an article of manufacture for use with freight loading equipment of the type described, a supporting member having an elongated main body portion and having holding means adjacent each end thereof to support said member and having a row of holding means along its length to adjustably hold other members, said first holding means being mounted on and offset above and to one side of said body portion so that said body portion is below and depends from and is also laterally spaced from said first-mentioned holding means.

7. As an article of manufacture for use in freight holding equipment in freight cars or the like, a horizontal side bay member adapted to bridge between spaced upright posts having spaced holding means along their lengths, said

bay member having holding means adjacent its ends to cooperate with said first-mentioned holding means to adjustably secure said member to said uprights, and said bay member comprising an elongated steel member having an upper surface to be horizontally disposed and carrying a row of closely spaced holding means extending substantially throughout its length to support cooperating cross members, said upper surface of said steel member being spaced below said second-mentioned holding means whereby the load of said cross members resting on said surface holds said bay member in secured relation to said uprights.

8. As an article of manufacture for use in freight holding equipment in freight cars or the like, a horizontal side bay member adapted to bridge between spaced upright posts having spaced holding means along their lengths, said bay member having holding means adjacent its ends to cooperate with said first-mentioned holding means, and said bay member comprising a steel angle having a row of spaced interengaging holding means extending along one leg thereof to be engaged with corresponding interengaging and holding means on cross bars to be secured on and between such bay members along opposite sides of the car or the like, the other leg of said angle affording an abutment surface for engagement with said side posts and cooperating therewith to retain said respective holding means in cooperative relation.

9. As an article of manufacture for use in freight holding equipment in freight cars or the like, a bay member adapted to horizontally bridge between spaced upright posts having spaced holding means along their lengths, said bay member having a row of spaced holding means extending along that surface thereof which is uppermost when the bay member is in place for engagement by corresponding holding means on cross bars to be secured on and between such bay members positioned at opposite sides of the car or the like, said bay member having adjacent each end thereof a supporting bracket, each said bracket being jaw-like so that it embraces a corresponding said upright post, and being provided with holding means which engage the holding means on said post, whereby said bay member is vertically supported, said uppermost surface being vertically and laterally offset from said brackets so that vertical loads applied to said bay member by a said cross member tend to rock the bay member about its longitudinal axis and augment said vertical supporting connection.

10. As an article of manufacture for use in freight holding apparatus for a freight car or the like, the combination of an elongated freight-holding member having extending lengthwise along at least one surface thereof, a row of tooth-like projections, the crests of said projections and the spaces therebetween being rounded, and the crests and spaces being joined by sloping sides, said projections being disposed to cooperate with complementary holding means of associated freight-holding members and the rounded character thereof and the slopes of the sides between teeth enabling a wave-like relative sliding motion between the associated holding means and the member in a direction lengthwise of the row while said projections and holding means are lightly pressed together.

11. A bridging member forming a part of loading equipment for freight cars, or the like, and

disposed to extend between and be supported by spaced supporting members having exposed and spaced opposite faces at least one of which has spaced tooth-like projections thereon, said 5 said bridging member being of elongated form having a pair of holding means spaced apart along its length for cooperation with said supporting members to effect said support, each said holding means comprising spaced portions at least one of which is fixedly secured to said bridging member and which portions are disposed to embrace a portion of the corresponding supporting member and engage the corresponding said two opposite faces thereof, at least one of said portions comprising a plurality of spaced tooth-like projections disposed to interlockingly engage said tooth-like projections on the corresponding one of said opposite faces, said spaced portions being so constructed and arranged that said bridging member is movable as a whole along said supporting members while maintaining said embracing relation.

12. Adjustable load-holding apparatus for a freight car, or the like, comprising generally parallel spaced elongated members, an elongated bridging member, inter-acting fixed holding members extending along the lengths of said spaced members and adjacent the ends of said bridging member, said holding members including means to permit manual adjustment of said bridging member along said spaced members upon a tilting movement of said bridging member, and means to permit removal of said bridging member from said spaced members only upon a tilting movement of said bridging member about an axis transverse to the axis of said first-mentioned tilting movement.

13. In freight loading apparatus, the combination of generally parallel spaced elongated members, holding means distributed along said members lengthwise thereof, an additional supporting member having engaging means spaced along its length detachably engageable with said holding means to removably secure said additional member between said first-mentioned members at a desired point therealong, said additional member being tiltable, in at least one direction, about an axis generally parallel to its length from said secured position to a position in which said holding and engaging means are disengaged from each other, said holding and engaging means being so disengageable only by a said tilting movement, said additional member being adjustable relative to said first-mentioned members when said means are so disengaged, said additional member having further holding means spaced along its length for cooperation with means to be supported by said additional member.

14. In freight loading apparatus, the combination of generally parallel spaced elongated members, said members each being provided with a series of tooth-like projections arranged lengthwise thereof, and an elongated additional member having engaging means spaced along its length detachably engageable with said projections to removably secure said additional member between said first-mentioned members at a desired point therealong, said engaging means comprising a plurality of projections which are complementary to the first-mentioned projections and mesh therewith, said additional member being tiltable, in at least one direction, about an axis generally parallel to its length from said

secured position to a position in which said projections are disengaged from each other, said additional member being adjustable relative to said first-mentioned members when said projections are so disengaged, said additional member having further holding means spaced along its length for cooperation with means to be supported thereby.

15. In freight loading apparatus, the combination of generally parallel spaced elongated members, holding means distributed along said members lengthwise thereof, an additional supporting member having engaging means spaced along its length detachably engageable with said holding means to removably secure said additional member between said first-mentioned members at a desired point therealong, said additional member being tiltable, in at least one direction, about an axis generally parallel to its length from said secured position to a position in which said holding and engaging means are disengaged from each other, said additional member being adjustable relative to said first-mentioned members when said means are so disengaged, said additional member having further holding means spaced along its length for cooperation with means to be supported by said additional member, and additional means cooperating between said additional member and said first-mentioned members for limiting relative movement therebetween in a direction lengthwise of said additional member.

16. In a freight car, or the like, having longitudinally spaced upright side posts forming part of the car sides, holding means at different elevations on said posts, and an elongated supporting member having engaging means spaced along its length detachably engageable with said holding means to removably secure said supporting member between said posts at a desired elevation, said member being tiltable, in at least one direction, about an axis generally parallel to its length from said secured position to a position in which said holding and engaging means are disengaged from each other, said holding and engaging means being disengageable only by a said tilting movement, said member being adjustable relative to said posts when said means are so disengaged, said member having further holding means spaced along its length for cooperation with means to be supported by said member.

17. In a freight carrying vehicle having spaced upright side posts, an elongated supporting member to bridge said posts, and interengaging holding means at different elevations on said posts on surfaces thereof not facing the inside of the vehicle for engagement with freight and at the end portions of said supporting member for ready removal or securing of said supporting member at a desired elevation between said posts only by a tilting of said supporting member about a generally longitudinally-extending axis of said supporting member.

18. In a freight carrying vehicle having spaced upright side posts, an elongated supporting member to bridge said posts, and interengaging holding means at different elevations on said posts and adjacent the ends of said supporting member formed and positioned for disengagement or locking engagement by only a tilting movement of said supporting member about a generally longitudinally-extending axis of said supporting member, to thus permit rapid removal or securing of said

supporting member between said posts at any one of a plurality of different elevations.

19. In a freight storage enclosure having side walls, spaced elongated side members having a row of holding means extending along their lengths on their back or outer faces to avoid any possible contact with freight, and elongated supporting members bridging said first members at desired positions therealong and having fixed engaging means adjacent their ends constructed and arranged to be selectively engaged with or disengaged from said holding means only by a tilting of said supporting members about axes parallel to their lengths.

20. Adjustable load bracing means in combination with a freight vehicle having side walls with spaced elongated members forming a part thereof and having side flanges, each having engaging means extending along one face of each flange, and elongated members adjustably positioned bridging between said first members and having adjacent their ends cooperating holding means to be engaged or disengaged only by a tilting of said second member about a longitudinal axis and including spaced means to embrace the edge of and to engage both faces of said side flange.

21. Apparatus as defined in claim 16, including releasable latch means acting between the loading and supporting members and normally effective to prevent said tilting movement.

22. In loading equipment for freight cars, or the like, spaced supporting members having plate-like portions extending lengthwise thereof, each plate-like portion having along one face thereof a succession of tooth-like projections, and an adjustable bridging member extending between and supported by said first-mentioned members, said bridging member having holding means spaced along its length for cooperation with said first-mentioned members to effect said support, each said holding means comprising, in fixed relation to said bridging member, a plurality of tooth-like projections complementary to said first-mentioned projections for engagement therewith, and a holding surface disposed to bear against the surface of the corresponding plate-like portion which is opposite to the tooth-like projections thereon.

23. As a subcombination in adjustable loading equipment for freight cars, or the like, longitudinally-spaced uprights forming parts of the car side frames and having at each side thereof, and substantially throughout the car height, a flange with a row of engaging portions opening or facing normally to the car side from one side of said flange, and vertically adjustable side members bridging adjacent uprights, adapted to support load bracing means, and having spaced along their lengths locking means including spaced fixed portions to embrace said flange with certain of said fixed portions engaging said engaging portions.

24. In a freight bracing or holding apparatus, spaced elongated supporting members each having a row of engaging shapes extending along a side thereof, a panel between said members but spaced therefrom to provide slots between the panel and the respective members, and a second movably adjustable elongated member having a holding means adjacent each end including a correspondingly-shaped set of engaging shapes to engage at a selected position along said row, and said second member constructed and arranged to have its holding means removed from or inserted in said slots while said second member is tilted about a transverse axis and to be

adjusted along said rows while tilted about a longitudinal axis.

25. A railroad freight car, or the like, having means forming side walls including inwardly-projecting metal posts with substantially flat, exposed inner surfaces, load bracing or supporting apparatus including holding means positioned at different elevations and extending substantially throughout the heights of said posts, and members having holding means thereon cooperating with said first holding means to adjustably secure said members at desired elevations between certain of said posts, said first holding means including portions at the sides of said posts and said second holding means including portions extending alongside of said posts to cooperate with said first portions, and cushioning lining members, substantially filling the spaces between said longitudinally-spaced posts and having their upright edges spaced sufficiently from the sides of said posts to permit entry of said second-mentioned portions, the inner and exposed surfaces of said lining members being substantially flush with the inner exposed surfaces of said posts to form a smooth freight-protecting inner car wall surface.

26. In freight loading apparatus for use in a freight car, or the like, the combination of spaced, generally parallel elongated supporting members, a bridging member extending between and supported by said first-mentioned members, said bridging and first-mentioned members having co-engaging holding portions which effect said support, and when in holding engagement secure said bridging member in place on said supporting members, said holding portions being constructed and arranged so that, while supported by said supporting members, said bridging member can be advanced along said supporting members during which advance said holding portions ride into and out of holding relation to each other.

27. In freight loading apparatus for use in a freight car, or the like, the combination of spaced generally parallel elongated supporting members, a bridging member extending between and supported by said first-mentioned members, said bridging and first-mentioned members having co-engaging holding portions which effect said support, and when in holding engagement secure said bridging member in place on said supporting members, said holding portions being constructed and arranged so that, while supported by said supporting members, said bridging member can be advanced along said supporting members during which advance said holding portions ride into and out of holding relation to each other, and latch means for securing said bridging member in selected positions of adjustment along said supporting members.

28. In freight loading apparatus for use in a freight car, or the like, the combination of spaced generally parallel, elongated supporting members, a bridging member extending between and supported by said first-mentioned members, said supporting members each having a succession of tooth-like projections distributed lengthwise thereof, and said bridging member having heads adjacent the ends thereof, each said head being provided with a succession of tooth-like projections which are complemental to and mesh with said first-mentioned projections, said projections being so formed that while said bridging member is supported by said supporting members, said bridging member can be advanced therewith, during which advance said tooth-like pro-

jections ride into and out of meshing relation to each other.

29. In freight loading apparatus for use in a freight car, or the like, the combination of spaced generally parallel elongated supporting members, a bridging member extending between and supported by said first-mentioned members, said supporting members each having a succession of tooth-like projections distributed lengthwise thereof, said bridging member having heads adjacent the ends thereof, each said head being provided with a succession of tooth-like projections which are complemental to and mesh with said first-mentioned projections, said projections being so formed that while said bridging member is supported by said supporting members, said bridging member can be advanced therewith, during which advance said tooth-like projections ride into and out of meshing relation to each other, and latch means carried by said bridging member for securing said bridging member in selected positions of adjustment along said supporting members.

30. In a freight car, or the like, at least one pair of generally parallel, elongated, substantially horizontally extending supporting members, said members disposed adjacent respectively opposite sides of the car so as to define a freight space therebetween, holding means including closely spaced tooth-like projections arranged along the length of each said supporting member, a load holding or bracing cross bar, holding means at each end thereof including projections meshing with projections on said supporting members to hold said bar in adjusted position between said supporting members, both sets of said meshing projections having rounded crests so that said bar while supported on said supporting members, can be advanced therewith along with a wave-like motion.

31. In a freight car, or the like, at least one pair of generally parallel, elongated, substantially horizontally extending supporting members, said members being disposed adjacent respectively opposite sides of the car so as to define a freight space therebetween, holding means including closely spaced tooth-like projections arranged along the length of each said supporting member, a load holding or bracing cross bar, holding means at each end of the bar and positioned substantially on the axis thereof, each holding means including a surface having projections meshing with projections on said supporting members to hold said bar in adjusted position between said supporting members, and latch means carried by the bar and including means engageable with the side supports to prevent disengagement of said meshing projections.

32. Freight holding equipment for use in a freight car, or the like, comprising substantially horizontal longitudinally-extending members secured along the respectively opposite walls of the car, said members having distributed lengthwise thereof along a horizontal surface thereof a plurality of upwardly directed closely spaced engaging shapes, a load holding cross member having adjacent each end a surface which has a complementally-shaped group of engaging shapes disposed to rest on and engage with the first-mentioned engaging shapes to prevent movement of the cross member along said first members, separate movable latch means associated with the respective ends of the cross member for preventing disengagement of said engaging shapes in a vertical direction, and hook means to limit

relative movement between said co-engaged engaging shapes in a direction transverse to the length of said first-mentioned members.

33. Freight holding equipment for use in a freight car, or the like, comprising laterally spaced supporting members arranged on opposite sides of a freight space a plurality of cross bars disposed to extend transversely across said freight space between said spaced supporting members, and means to secure the ends of said bars to said supporting members in selected vertically or horizontally adjusted positions to said supporting members, said securing means comprising two pairs of cooperating inter-fitting toothed surfaces, one said surface of each pair being carried by each said bar at each end thereof, the other said surface of each pair being carried by the corresponding supporting member, and separate latch means carried by each bar at each end thereof to hold said toothed surfaces against disengagement in a direction normal to said surfaces.

34. Freight holding equipment for use in a freight car, or the like, comprising substantially horizontal longitudinally-extending members secured along and with respect to the opposite car walls, said members having distributed lengthwise along a horizontal surface thereof a plurality of upwardly-directed closely spaced engaging shapes, a load-holding cross member having adjacent each end a supporting head, each head having surface which is immovable with respect to the associated head and which has a complementally-shaped group of engaging shapes resting on and engaged with said first shapes to prevent movement of said cross member along said first members, and separate movable latch means carried by each head and engageable with other surfaces of said first-mentioned members to prevent disengagement of said respective shapes.

35. Loading apparatus for a railway box car, or the like, comprising longitudinally-spaced posts affixed at the sides of the car and having means providing a row of tooth-like projections extending substantially from the floor to the roof, vertically adjustable side members bridging adjacent posts and having locking means including portions with means fitting and interengaging a group of selected adjacent projections on said posts, said side members being adapted collectively to extend in adjoining relation from one end of the car to the other, and each side member having a row of engaging portions extending therealong from end to end, and adjustable cross bars disposed transversely to the car and having locking means including corresponding engaging portions adjacent the ends thereof interengaging a group of selected adjacent engaging portions of said side members.

36. Loading apparatus for a railway box car, or the like, comprising longitudinally-spaced posts affixed at the sides of the car and each having means providing a row of tooth-like projections at each side thereof and extending substantially from the floor to the roof, vertically adjustable side members bridging adjacent posts and having locking means including portions with means fitting and interengaging a group of selected adjacent projections on said posts, said side members being adapted collectively to extend in adjoining relation from one end of the car to the other, and each side member having a row of tooth-like projections forming engaging portions extending therealong from end to end, and adjustable cross bars disposed transversely of the

car and having locking means including corresponding engaging portions adjacent the ends thereof interengaging a group of selected adjacent engaging portions of said side members.

37. Loading apparatus for a railway box car, or the like, comprising longitudinally-spaced posts affixed at the sides of the car and each having means providing a row of tooth-like projections at each side thereof and extending parallel to the planes of the car sides and substantially from the floor to the roof, vertically adjustable side members bridging adjacent posts and having locking means including portions with means fitting and interengaging a group of selected adjacent projections of said posts, said side members being adapted collectively to extend in adjoining relation from one end of the car to the other, and each side member having a row of engaging portions extending therealong from end to end, and adjustable cross bars disposed transversely of the car and supported by said side members, said bars having holding means including corresponding engaging portions adjacent the ends thereof interengaging a group of selected adjacent engaging portions of said side members to effect said supports, said holding means being arranged so that cross bars can, while supported as aforesaid, be advanced along said side members.

38. In combination with a freight car or the like, having a series of spaced interengaging holding means along its side walls, longitudinally spaced transverse cross bars having cooperating interengaging securing means adjacent their ends adjustably engaged with certain of said side wall holding means in a desired adjusted position therealong, said cross bars having a series of spaced interengaging holding means along their lengths between their end securing means, a longitudinally-extending bar having interengaging securing means adjacent its ends and engaged with certain of said series of holding means along the length of said spaced cross bars and thus secured in desired adjusted position therebetween, said longitudinally-extending bar also having a series of spaced interengaging holding means along its length between its end securing means, and a shorter freight holding cross bar extending only part way across the width of the freight car and having adjacent its ends interengaging securing means engaged with certain of said side wall holding means and the holding means along the length of said longitudinally-extending bar to secure said shorter cross bar in desired adjusted position therebetween.

39. As an article of manufacture, a freight holding cross bar having interengaging securing means adjacent each end thereof for holding it in a desired adjusted position between and with its securing means interengaged with certain of a series of interfitting holding means spaced along the opposite side walls of a freight car or the like, and said bar having a series of spaced holding means along its length between its end securing means to interengage with and to secure in desired adjusted positions therealong the corresponding interengaging securing means adjacent the ends of other bars to thus form in a freight car or the like, side by side bins, central, vertical partitions, horizontal partitions, platforms or holddowns secured between spaced cross bars across the car, or other arrangements.

40. As an article of manufacture, a freight-holding bar adapted to rest on and be adjusted along and to be secured between two spaced rack members each having a toothed upper surface,

an under surface, and a side surface, said bar comprising an elongated member, a metal member fixed to each end thereof having a projecting portion with a plurality of teeth to mesh with the teeth of said rack members, a portion to engage over the side surface of said rack members to prevent longitudinal disengagement of said teeth, and a manually adjustable, movable portion to engage the under surface of the corresponding said rack member to secure the corresponding teeth in meshed relation to said corresponding rack member.

41. A bridging member for forming a part of loading equipment for freight cars, or the like, and disposed to extend between and be supported by spaced horizontally extending supporting members having exposed and spaced opposite faces at least an upper one of which has spaced tooth-like projections thereon, said bridging member being of elongated form having a pair of heads adjacent its ends for cooperation with said supporting members to effect said support, each said head comprising spaced portions one of which is fixedly carried by the associated head and the other of which is movable relative to said associated head between holding and retracted positions, said one of said portions comprising a plurality of spaced tooth-like projections disposed to interlockingly engage said tooth-like projections on the corresponding one of said opposite faces, the form and inclination of the sides of said projections being such that, while said projections are in said engagement and said other portions of said heads are retracted, said bridging member can be advanced along said supporting members with a wave-like motion, said other

portions when in holding positions being disposed to engage the said opposite faces and thereby prevent said motion and lock said bridging member in adjusted position.

- 5 42. The structure of claim 41 wherein said other portions are swingable in moving between their said positions about axes normal to the length of the bridging member and normal to the direction of a said advancing movement.
- 10 43. In freight loading apparatus for use in a freight car, or the like, the combination of spaced generally parallel elongated supporting members, a bridging member extending between and supported by said first-mentioned members, said supporting members each having a succession of tooth-like projections distributed lengthwise thereof, said bridging member having heads adjacent the ends thereof, each said head being provided with a succession of tooth-like projections which are complementary to and mesh with said first-mentioned projections, said projections being so formed that while said bridging member is supported by said supporting members, said bridging member can be advanced therewith, during which advance said tooth-like projections ride into and out of meshing relation to each other with a wave-like motion, and releasable latches carried by said bridging member and movable into positions in which they engage said supporting members and block said wave-like motion thereby locking said bridging member against further movement along said supporting members.
